United States Patent Office.

ALVAH WORSTER, OF HANNIBAL, NEW YORK.

Letters Patent No. 91,807, dated June 22, 1869.

IMPROVED TRACE-BUCKLE.

The Schedule referred to in these Letters Patent and making part of the same.

To all whom it may concern:

Be it known that I, ALVAH WORSTER, of Hannibal, in the county of Oswego, and State of New York, have invented a new and useful Improvement in Trace-Buckles, and I do hereby declare that the following is a full, clear, and exact description thereof, which will enable those skilled in the art to make and use the same, reference being had to the accompanying drawings, forming part of this specification, in which—

Figure 1 is a front view;

Figure 2 is an edge view; and

Figure 3 is a sectional edge view.

Similar letters of reference indicate like parts in all the figures.

This invention consists in a buckle, having a swinging loop, or link, which, with the buckle-frame, is secured permanently to the hames-tug, and in using, in connection therewith, a tongue, mounted on a plate, or bar, made to slide in said loop, in such manner that the buckle is opened or closed, by the movement of said bar within the loop, and by the swinging movement of the loop, as hereinafter more fully explained.

In the accompanying drawings—

A is the hames-tug;

C is the buckle-frame;

E is the loop, or swinging link; and

F is the tongue-plate, or bar.

The buckle-frame C is cast with a plate, c, by which it is secured to the hames-tug, by rivets or other suit-

able means; and said plate is provided with a notch, g, figs. 2 and 3, which holds the loop E, in such manner that the wear caused by the loop comes upon the plate c, instead of the hames-tug.

The plate, or bar F is cast with a tongue, f, fig. 3, which engages with holes in the tug, and has shoulders h h', for retaining it in the loop.

When a strain is brought upon the tug, the bar F is drawn back until its shoulder h bears upon the loop, and the bar is then pressed toward the plate c, so that the tug is clamped securely between them, and the tongue f thereby relieved of much strain, and the tug held without liability of being torn by the tongue, the clamping-pressure being obtained by the swinging movement of the link F.

By these means, I obtain a very efficient and desirable buckle.

Having thus described my invention,

What I claim as new, and desire to secure by Letters Patent, is—

The combination of the frame C, swinging link E, and plate, or bar F f, constructed and operating substantially as and for the purpose described.

The above specification of my invention signed by me, this 21st day of September, 1868.

ALVAH WORSTER.
